United States Patent Office.

JAMES WALBER, OF WASHINGTON, DISTRICT OF COLUMBIA

Letters Patent No. 64,049, dated April 23, 1867.

IMPROVEMENT IN MACHINE FOR FELTING HAT-BODIES.

The Schedule referred to in these Letters Patent and making part of the same.

TO ALL WHOM IT MAY CONCERN:

Be it known that I, JAMES WALBER, of the city of Washington, and District of Columbia, have invented a new and improved Machine for Felting Hat-Bodies; and I do hereby declare that the following is a full, clear, and exact description of the construction and operation of the same, reference being had to the accompanying drawings, making a part of this specification, in which—

Figure 1 is a plan view of my improved machine for felting hat-bodies.

Figure 2, a transverse section taken in the plane $x y$ of fig. 1.

Figure 3, a longitudinal side elevation.

Figure 4, a view in detail of adjusting arrangement for gearing.

Figure 5, a view in detail of journal-box of driving-shaft of roller in a sliding-way of the machine.

Like letters in the different figures of the drawings indicate like parts.

The nature of my invention consists in the following improvements in the construction of machines for felting hat-bodies: First, diminishing the speed of revolution in each successive pair of rollers from the front or feeding end of the machine to the rear, so far as may be found expedient, for the purpose of compacting the material. This I effect either by slightly reducing the diameter of each successive pair of rollers, or, where all the rollers are of uniform diameter, by any proper adjustment of the gearing of said rollers. Second, in the employment of a single endless chain, in combination with toothed wheels upon the ends of two series of rollers in the place of cogged gearing; for the purpose of imparting the required rotary movement. Third, placing the journal-boxes of the driving-shaft in sliding-ways to permit the adjustment of the endless chain connecting said shaft with the several rollers, and the combination therewith of suitable springs or weights to maintain a constant tension of said chain. Fourth, extending the journals of the lower rollers, so as to allow them lateral movement in their bearings, and imparting a constant reciprocating movement to each in its bearings by means of cams upon the outer ends of its journals working against suitable fixed cam surfaces. Fifth, constructing the lower rollers which revolve successively with diminished speed, hollow, to be heated by passing a current of steam through the same. Sixth, constructing a reversing roller placed in the rear end of the machine to return the felted fabric to the front, with an auxiliary roller placed over the same, to bear thereon and operate conjointly therewith.

My improved machine is constructed of a series of rollers, A A' A'', B B B, arranged horizontally in pairs, the two in each pair being placed one above the other. The journals of the upper rollers are supported in suitable boxes formed in plates C, which play vertically in suitable grooves or ways formed in the frame of the machine, or between vertical standards D D, figs. 1 and 5, arranged to support them, and which form part of the frame. Weights E E, figs. 1 and 3, are provided to rest upon these sliding plates C to bear down the upper rollers upon those beneath with such degree of pressure as may be found expedient, these weights being kept in position by upright rods α , fig. 3, projecting from the standards through apertures in said weights. The three last pair of rollers B B B are of equal diameters, but each pair A A' A'' in front of these are made successively to increase slightly in circumference. Each roller in the machine is provided with a toothed wheel, F, secured upon the outer end of one of its journals, said toothed wheels being placed alternately upon the upper and lower roller in each pair on each side of the frame. Cams $b b$, fig. 2, are formed upon the outer end of each lower roller, either upon the extended journal or upon the face of the toothed wheel secured thereon which bear against stationary pins or plates $c c$; the position and inclination of the two cams upon the ends being reversed so as to cause in the revolution of the roller a reciprocating movement thereof in its bearings. These lower rollers and their journals are formed hollow, as illustrated in fig. 2. One end of each is fitted to receive at its centre or axis, loosely but snugly, the nozzle of a pipe, d, branching from a main steam pipe, G, placed for the purpose along each side of the frame of the machine, whilst the other is left open to admit of the discharge of the steam and water condensed therefrom. Steam is thus admitted to these lower rollers alternately from each side of the machine through the end of each roller which carries its toothed wheel. In the rear of the lower rollers, and in the same axial plane therewith, is placed a driving-shaft, H, provided with toothed wheels at both ends similar to those upon the rollers. Endless chains K K, formed of square open links so proportioned as to engage fairly with the several toothed wheels F F, are arranged on each side to pass over and around the toothed wheels of the driving-shaft H at one end and of the lower roller or of an extra wheel L, at the other, the upper stretch of each chain passing between the toothed wheels on the upper and lower rollers engaging with the teeth of each, whilst the lower stretch lies free and disengaged below them, as seen in fig. 1. Thus the motion communicated to the driving-shaft H is readily imparted to each of the rollers without the expensive and intricate train of cogged wheels usually adopted. In order to keep the endless chains K under proper tension, and yet allow them to adapt themselves to the varying vertical as well as the lateral movements of the rollers, the journal-

boxes of the driving-shaft are arranged to slide in horizontal ways or slots $h\ h$, fig. 4. Pivoted levers $M\ M$ figs. 3 and 4, whose arms move in a vertical plane, swing and bear against the journal-boxes to push them outwardly in the ways $h\ h$, the pressure being obtained by means of springs N , attached to the upper free ends of the arms. Instead of interposing levers to obtain the elastic tension upon the chain, springs may be secured to or combined directly with the sliding journal-boxes. An auxiliary reversing roller, O , is placed in the rear of the operating rollers $A\ B$, in close proximity to the last pair B thereof, with its axis in a plane midway between the axis of said rollers. This roller is made to revolve in a direction opposite to that of the operating rollers. A second smaller roller, P , is placed immediately over it and left free to rest upon it. A vat of warm water is so arranged beneath the machine as that the lower operating rollers shall barely dip therein, and their surfaces are thus kept continually moist when in use. They are at the same time kept heated to a proper temperature by the steam made to pass through them.

In the operation of the machine the hat-bodies are fed in between the two front rollers $A\ A$, which compress and pass them to the next pair. As the first pair, $A\ A$, owing to their larger diameter, have a more rapid movement than the second, $A'\ A''$, the material is crowded and compressed or "butted" against the latter, and consequently passes between them with a closer, more compact tissue; the same result is obtained in the passage of the material from the second $A'\ A''$ to the third pair, $A''\ A''$, of rollers, and may be continued yet longer by increasing the number of rollers of diminishing diameters. The last three pair, $B\ B$, of rollers are left of uniform diameter to finish completely, compacting and condensing the fibres compressed by the first series of rollers. The constant reciprocating movement of the lower rollers in a direction transverse to the movement of the felted material serves to give the required rubbing and felting to the same as it passes over them. When the hat-bodies pass from the last pair of rollers they butt against the reversing roller O , which, revolving in an opposite direction, carries them immediately upwards, and, together with the small auxiliary roller P resting thereon, throws them back upon the upper rollers whose revolutions serve to carry them to the front. The degree of pressure exerted upon the material is regulated by means of the weights bearing down on the upper rollers, whilst the action of the levers and springs M and N upon the sliding journal-boxes of the driving-shaft maintains automatically a proper adjustment of the endless chains K to the variation of the upper rollers, caused by the different thicknesses of the hat-bodies passed through the machine. As the "butting" or thickening of the felted hat-bodies is obtained in my machine by diminishing the speed in revolution of successive pairs of rollers, I contemplate any mode of obtaining and adjusting the same, and do not limit myself to the use of rollers of varying diameters, but contemplate using rollers of equal diameters, and retarding the revolution of successive pairs thereof by suitable combinations of cogged gearing, or by diminishing the number of teeth in the toothed wheels F , combined with an endless chain, K , as illustrated in the accompanying drawings, or in any other suitable manner. I contemplate also any suitable arrangement of cams $b\ b$ upon the ends of the rollers to impart thereto the required reciprocating movement, my invention having reference to the use, in machines for felting hat-bodies, of rollers having reciprocating movements in their bearings, independent of the stationary frame which supports them however such reciprocating movements may be imparted thereto.

Having thus fully described my improved machine for felting hat-bodies, what I claim therein as new, and desire to secure by Letters Patent, is—

1. The combination and arrangement, in a machine for felting hat-bodies, of two or more pairs of rollers having a rotary movement, when each successive pair revolves with a diminished speed, all substantially in the manner and for the purpose as herein set forth.
2. The combination, as above, of two or more pairs of rollers whose diameters so vary as that the circumference of each successive pair shall revolve with diminished speed, substantially in the manner and for the purpose as herein set forth.
3. The combination, in a felting machine, of a series of pairs of rollers, each pair of which has a lesser velocity than the preceding pair, with a series of pairs of rollers having a uniform velocity, as and for the purpose herein described.
4. The combination, in a felting machine, of a series of rollers supported in a fixed frame but each having an independently lateral play in its bearings in the line of its axis, substantially as and for the purpose herein described.
5. Imparting a lateral reciprocating movement to the rollers of a machine for felting hat-bodies by means of cams on the ends of said rollers, or their journals bearing against suitable cam surfaces, when each of said rollers has free play independently of the others in the line of its axis, all substantially in the manner and for the purpose herein set forth.
6. The use of a series of hollow rollers in a felting machine, with suitable steam pipes for introducing steam into the same when said rollers revolve successively with a diminished speed, substantially in the manner and for the purpose herein set forth.
7. The combination of a reversing roller, placed centrally in front of the last pair of rollers in a felting machine, with an auxiliary roller placed over the same to bear thereon and operate conjointly therewith, substantially in the manner and for the purpose herein set forth.
8. The combination of a single endless chain and toothed wheels with two series of rollers in a felting machine, substantially as and for the purpose herein described.
9. The combination of suitable springs with the sliding journal-boxes of the driving-shaft, and with an endless chain working thereon, all substantially as and for the purpose herein set forth.

JAMES WALBER.
